E. Hall,

Tool Handle,

No 10,504,

Patented Feb. 7, 1854.

UNITED STATES PATENT OFFICE.

ELIAS HALL, OF RUTLAND, VERMONT.

TOOL-HOLDER.

Specification of Letters Patent No. 10,504, dated February 7, 1854.

To all whom it may concern:

Be it known that I, ELIAS HALL, of Rutland, in the county of Rutland and State of Vermont, have invented a new and useful 5 Instrument or Universal Tool-Holder to be Used as a Handle for Bits and other Tools, of which the following is a full and exact description, reference being had to the accompanying drawings and the letters of reference on it.

10 My invention consists in adapting to a common handle a shank so contrived that any bit or other tool of the kind, as a gimlet, file, screw driver and the like, may be inserted with facility, and held perfectly firm 15 while in use, and readily removed when another is to be employed.

15 The handle and shank, with a screw driver, (as an example) inserted, are shown 20 in Figures 1 and 2. The shank (*a*) made of iron or other metal is wrought at the end into a short square socket, tapering toward the handle, and intended to hold the tool to be used. Back of the socket the shank is 25 flat, with a hole (*b*) through it, close to the socket and of the same width. The bit or other tool to be used should be made to fit the socket and project through into the hole (*b*). On the flat side of the shank is 30 screwed a spring (*c*) flat, and straight, or very slightly bent, with a tooth or catch upon the under side of it (see Fig. 3) so that this tooth drops into the hole (*b*), made through the shank. On one side of the tool 35 should be made a notch so as to receive this tooth and keep the tool firmly in its place. When the tool is to be removed the spring and tooth are raised by a screw, with a broad head or thumb piece (*d*) which moves 40 freely through the shank, and is firmly screwed into the spring, as seen in Fig. 2.

A screw may also be inserted through the shank, near this thumb piece, so as to press against the under spring, and when turned to keep it raised when desired.

45 I am aware that instruments somewhat similar have been used, and that this nearly resembles a bit-stock. But in their construction and especially in the application of the spring my invention is greatly superior. 50 No other instrument of the kind has before been constructed so that it could be seen where the notch should be made upon the tool to receive the tooth of the spring. Hence it has been found difficult to have 55 every tool used in such an instrument firmly held, and it is only effected by repeated experiments and trials in making the notch. While in the instrument above described it 60 can be seen at once exactly where the notch should be made so as to retain the tool when steadily and firmly held by the socket. Besides, I am not aware that any such contrivance has ever been employed in an instrument to be held and used in one hand, 65 or with a common handle.

What I claim therefore as my invention and desire to secure by Letters Patent, is—

Having a flat spring catch inserted in the side of the stock or handle, with an opening 70 through the stock or handle in a line with the catch of the spring, by which you are enabled to see and mark on the shank of the tool held the point touched by the catch of the spring when the shank is pressed home 75 in the socket, and thus readily mark the recess or notch in the shank.

ELIAS HALL.
